(57) **CLAIM**

The design for a guide jacket force sensor, substantially as shown.

DESCRIPTION

FIG. 1 is a perspective view of the sensor with lead carrier and leads on the carrier and on the sensor body shown in dotted lines;

FIG. 2 is top view of the sensor with lead carrier;

FIG. 3 is a bottom view of the sensor with lead carrier;

FIG. 4 is a left side view of the sensor with lead carrier;

FIG. 5 is a right side view of sensor with carrier;

FIG. 6 is a left end view of the sensor with carrier;

FIG. 7 is a right end view of the sensor with lead carrier;

FIG. 8 is a perspective view of the sensor alone;

FIG. 9 is a top view of the sensor alone;

FIG. 10 is a bottom view of the sensor alone;

FIG. 11 is a left side view of the sensor alone;

FIG. 12 is a right side view of the sensor alone;

FIG. 13 is a left end view of the sensor; and

FIG. 14 is a right end view of the sensor.

FIG. 15 is a perspective view of a second embodiment with no jacket;

FIG. 16 is a top view of the second embodiment;

FIG. 17 is a bottom view of the second embodiment;

FIG. 18 is a left side view of the second embodiment;

FIG. 19 is a right side view of the second embodiment;

FIG. 20 is an end view of the second embodiment; and,

FIG. 21 is an opposite end view of the second embodiment.
